(57) **CLAIM**

The ornamental design for a sprinkler head leveling and adjustment device, as shown and described.

DESCRIPTION

FIG. 1 is an isometric view of a sprinkler head adjustment and leveling device showing my new design.

FIG. 2 is a front elevation view thereof.

FIG. 3 is a top plan view thereof.

FIG. 4 is a left side elevation view thereof.

FIG. 5 is a right side elevation view thereof.

FIG. 6 is a rear elevation view thereof; and,

FIG. 7 is a bottom plan view thereof.

The broken lines shown in the drawings depict environment, and form no part of the claimed design.
